United States Patent Office

Des. 202,235
Patented Sept. 7, 1965

202,235

TYPEWRITER

Eliot Noyes, New Canaan, Conn., assignor to International Business Machines Corporation, New York, N.Y., a corporation of New York

Filed Sept. 14, 1964, Ser. No. 81,698

Term of patent 14 years

(Cl. D64—11)

FIG. 1

Des. 202,235

PAGE 2

FIG. 2

FIG. 3

FIG. 4

FIGURE 1 is a front view of a typewriter, showing my new design;

FIGURE 2 is a right side view thereof;

FIGURE 3 is a rear view thereof; and

FIGURE 4 is a top plan view thereof.

The dot-dash lines on the drawing indicate that the rows of keys extend across the keyboard.

I claim:

The ornamental design for a typewriter, substantially as shown and described.
